UNITED STATES PATENT OFFICE.

WILLIAM J. ABBOTT, OF ALGIERS, INDIANA.

DITCHING-MACHINE.

1,062,528.

Specification of Letters Patent.

Patented May 20, 1913.

Application filed May 3, 1912. Serial No. 694,847.

To all whom it may concern:

Be it known that I, WILLIAM J. ABBOTT, a citizen of the United States, residing at Algiers, in the county of Pike and State of Indiana, have invented new and useful Improvements in Ditching-Machines, of which the following is a specification.

This invention relates to ditching machines for forming ditches for the reception 10 of drain or other tiles, the object in view being to provide a simple, reliable and effective machine, which will not be burdensome on the draft animals, and which is provided with suitable adjustments, whereby the ditch 15 may be formed to any desired depth.

With the above and other objects in view, the invention consists in the construction, combination and arrangement of parts, as will be hereinafter more fully described, 20 illustrated in the accompanying drawings, and pointed out in the claims hereunto appended.

In the drawings: Figure 1 is a side elevation of a ditching machine, embodying the 25 present invention. Fig. 2 is a vertical central longitudinal section through the same. Fig. 3 is a plan view thereof. Fig. 4 is a rear elevation of the machine. Fig. 5 is a detail perspective view of the shiftable slide. 30 Fig. 6 is a similar view of the plow.

The ditching machine contemplated in this invention comprises a front axle 1, a rear axle 2, and carrying wheels 3. While the front carrying wheels are journaled on 35 the ends of the axle 1, the rear carrying wheels are fast on their axle, so that the axle 2 revolves for a purpose which will hereinafter appear.

The frame of the truck comprises the oppositely arranged and rearwardly diverging 40 reach bars 4, which are connected at the front by suitable cross bars 5, 6, 7 and 8, while connected to the rear ends of the reach bars 4 are two forwardly converging compression braces 9, the inner ends of which 45 are rigidly connected to the centrally arranged trough of the elevating conveyer, hereinafter particularly described.

Extending centrally and longitudinally of 50 the truck frame is an elevating conveyer, comprising essentially a trough-like receptacle, preferably formed out of sheet iron bent up to comprise a bottom 10, and parallel upstanding sides 11. This trough extends practically for the entire length of the machine, and is reinforced at the rear end

thereof by means of journal brackets or plates 12 which extend downward and form bearings in which the rear axle of the machine turns. In this way, the rear end of 60 the trough or conveyer is supported directly on the rear axle, while drag or pull on the rear axle is relieved by the special construction of truck frame, hereinabove described, and embodying the rearwardly diverging 65 reach bars 4 and the rearwardly diverging braces 9.

Mounted fast on the rear axle 2 is a spur gear wheel 13, which meshes with a pinion 14 fast on a short counter shaft 15 extending 70 through the plates or brackets 12. Fast on the same counter shaft 15 are the oppositely arranged sprocket wheels 16, around which run the chains 17 of an endless elevator carrier, said carrier comprising any suitable 75 number of flights or blades 18 which will obtain a hold on the material and carry the same rearwardly, where such material is deposited upon a spreader 19, consisting of a plate of sheet metal, bent into an inverted 80 V-shape in cross section and supported by parallel bars 20, extending rearwardly from the rear end of the conveyer frame to which said bars are connected. This spreader receives the earth discharged from the elevat- 85 ing carrier and serves to throw the earth to the sides of the ditch formed by the plow at the advance end of the elevating conveyer. The plow is also formed of sheet metal and is shaped like the trough in cross section, 90 comprising a bottom 21, and upstanding substantially parallel sides 22, while connected to the rear end of the plow is an inverted U-shaped yoke, embodying the top or connecting portion 23 and the down- 95 wardly extending arms 24 which are fixedly connected to the sides 22 of the plow, and extended below the bottom of the plow, where they are pivotally connected, at 25, to the advance end of the elevating conveyer. 100 This construction enables the plow to be rocked relatively to the conveyer, so as to change the pitch or angle of inclination of the plow to make it work with the greatest possible ease. 105

Extending upward from the top of the yoke is a rigidly attached standard 26 which passes through a slot 27 in a guide plate 28 resting upon the cross bars 5 and 6, and held in place by suitable keepers 29 secured 110 to said cross bars.

Connected to the rear end of the slide

28 is a link 30, the rear end of which is connected to a manually operated lever 31, fulcrumed on the cross bar 7 immediately adjacent to the driver's seat 32, which is 5 also mounted on the cross bar 7, as shown. The operator by a movement of the hand lever may slide the guide 28 forward and backward, causing the standard 26 to move correspondingly, thereby tilting the plow 10 so as to change the pitch, as required. The guide 28 is also formed with an opening 33, through which passes an elevating rope 34 having its lower end connected to the yoke of the plow, while said rope is wrapped 15 around a drum 35 of a windlass, the shaft 36 of which is provided with an operating crank 37 arranged within convenient reach of the operator on the machine. By means of the windlass, the advance end of the elevating conveyer may be raised and lowered, and the plow carried thereby will also be correspondingly raised and lowered. It will be observed, however, that the pitch or inclination of the plow may be varied, irrespective of the up and down adjustment of the advance end of the elevating conveyer.

It is preferred to design the driving gears which actuate the elevating conveyer, so as to secure a movement of said conveyer two 30 or more times as fast as the movement of the ditching machine. This will provide for a rapid transmission of the earth rearwardly and prevent any possibility of the elevating conveyer becoming congested. Furthermore, 35 in order to insure the driving of the elevating carrier, the rims of the rear driving wheels will be provided with traction ribs, similar to those employed in agricultural machinery in general.

40 What is claimed is:

1. A ditching machine, comprising a truck, an elevating conveyer extending centrally and longitudinally of the truck, a plow having a jointed connection with the 45 advance end of the conveyer, means for raising and lowering the advance end of the conveyer and the plow, and means for ad-

justing the pitch of the plow irrespective of the elevation of the advance end of the conveyer comprising a standard extending upward from the plow, and a manually operated device for shifting said standard forward and backward. 50

2. A ditching machine comprising a truck, an elevating conveyer extending centrally and longitudinally of the truck, a plow having a jointed connection with the advance end of the conveyer, means for raising and lowering the advance end of the conveyer and the plow, an arched yoke connecting the plow and the conveyer, a standard extending upward from said yoke, and a manually controlled shiftable guide through which said standard passes. 60

3. A ditching machine comprising a truck, an elevating conveyer extending centrally and longitudinally of the truck, a plow having a jointed connection with the advance end of the conveyer, means for raising and lowering the advance end of the conveyer and the plow, an arched yoke pivotally connected to the conveyer and fixedly connected to the plow, a standard extending upward from said yoke, and a manually controlled shiftable guide through which 75 said standard passes.

4. A ditching machine, comprising a truck, an elevating conveyer extending centrally and longitudinally of the truck, a plow having a jointed connection with the 80 advance end of the conveyer, an arched yoke connecting the plow and conveyer, a standard extending upward from said yoke, a manually controlled shiftable guide through which said standard passes, a windlass journaled on the machine frame, and a rope wound thereon and connected to said yoke. 85

In testimony whereof I affix my signature in presence of two witnesses.

WILLIAM J. ABBOTT.
